United States Patent Office

Des. 201,233
Patented May 25, 1965

201,233

DOMESTIC RANGE CABINET OR SIMILAR ARTICLE

Russell R. Dunbar, Detroit, Mich., assignor to General Motors Corporation, Detroit, Mich., a corporation of Delaware

Filed Jan. 8, 1964, Ser. No. 78,122

Term of patent 7 years

(Cl. D81—4)

Fig.1

Fig.2

7-1=

Fig.3

7-1=

FIGURE 1 is a front elevational view of a domestic range cabinet or similar article embodying my new design;

FIGURE 2 is a side elevational view thereof;

FIGURE 3 is a top plan view thereof;

FIGURE 4 is a left front perspective view thereof;

FIGURE 5 is a fragmentary sectional view taken along line 5-5 in FIGURE 3;

FIGURE 6 is a fragmentary sectional view taken along line 6-6 in FIGURE 7; and

FIGURE 7 is a fragmentary sectional view taken along line 7-7 in FIGURE 3.

The dominant features of the design reside in the portion shown in full line.

I claim:

The ornamental design for a domestic range cabinet or similar article, as shown and described.
